APPARATUS FOR DEFIBRATING HARD WOOD

Jean E. Arguillere, Saint Etienne De Rouvray, France

Application July 25, 1956, Serial No. 600,044

4 Claims. (Cl. 162—236)

The present invention relates to an apparatus for defibrating cuttings of hard wood chips which are floated in a liquid medium by mechanical and eventually chemical means under selected conditions of pressure and temperature.

However, in the paper-making industry, it is usual to give the name of chips to wood cuttings having a thickness of the order of several millimeters. In contradistinction, in the process of the invention, laminar cuttings are used which have a thickness of between one tenth and five tenths of a millimeter.

It is known that the standard defibrating is effected by grating, in the presence of water, wood presented as bars to the outer surface of a cylindrical defibrating wheel which is driven rotatively, the bars being placed parallel to the axis of the defibrating wheel, and by regulating the pressure of the bars on the defibrating wheel, the grain of the defibrating wheel, and the temperature, which is itself a function of the foregoing factors, as well as the temperature and the quantity of the added water.

On the other hand, it has been proposed to carry out the defibrating of textile materials in an aqueous medium in beaters with oscillating hammer or similar percussion members, which rotate inside a grinding chamber, the inside of the wall of which is provided with a coating of abrasive material. In these hammer beaters, the defibrating is effected by the shock action of the hammers and by the action of projection of the textile material against the wall of the grinding chamber, these actions effecting a disintegration of the structure of the textile material, and it is the plasticizing action of the water which protects the individual fibers from the destruction which is unavoidable in a dry medium.

The apparatus of the invention consists essentially of an annular grinding wheel which has secured to its internal cylindrical surface abrasive particles for abrading wood chips and vanes for driving the fibers cut and defibrated from the chips by said grinding wheel without percussive effect, said vanes being hollow and formed with perforations in order to supply water and, if required, the liquid chemical products for the desired chemical action to which the chips are to be subjected and for diluting the fibers at a screening station.

The fibrous material to be defibrated is driven in relation to the annular grinding wheel at the same time as the required quantity of water, to which chemical products may or may not have been added, by a device comprising vanes which are rotatable about the axis of the grinding wheel, and it is ground by the action of this circular movement with which it is driven and of the centrifugal force thus produced, by utilizing, at the same time, the speed, the pressure and the increase of temperature due to the friction and or produced artificially, regard being had to the addition of water, to which chemical products may be added if required. As in the standard defibrators, the apparatus combines a fiber-refining action with the grinding action proper.

The device renders it possible to work continuously by

2

feeding the apparatus continuously with fibrous material, with water and, if required, with the desired chemical products, and also by removing continuously the fibers in suspension.

5 It is known that disintegration of hard wood chips produces fibers which are shorter than the fibers produced by disintegration of resinous wood chips. In order for the hard wood fibers not to be unduly shortened, the fibers must be expelled from the defibrator as soon as they have 10 been reduced to a given desired length. Consequently the apparatus is provided with screening means and expelling means which permit the removal of the fibers or bundles of fibers in suspension as soon as their dimensions are less than the given dimensions.

15 It may be pointed out that the principle proposed remains the same if it is the grinding wheel which rotates, driving the cuttings and the water in its movement of rotation, the difference of speed between the cuttings and the surface of the grinding wheel being produced by a system such as stationary vanes.

It is possible to combine the two devices, it being possible for the vanes to rotate in the direction opposite to that of the grinding wheel.

One of the important points to be specified is that the 25 process renders it possible to combine the friction which gives rise to the grinding with conditions of pressure and of temperature which render possible a particular action on the fibrous material which it is desired to work and to do this in the actual grinding zone.

30 It has been observed that the turbulence created by the vanes in the centrifugal grinder of the invention resulted in emulsifying the air with the liquid, the cuttings and the fibers and that a certain quantity of air was removed at the same time as the good fibers; this produced a reduction of pressure inside the grinder.

35 The grinder of the invention possesses an airtight chamber for deaerating the cuttings (or the fragmentary fibrous vegetable matter) into which the cuttings are introduced by airtight means. A cooking liquor of delignifying products is also introduced into this chamber in an airtight manner, and the previous deaeration facilitates the impregnation of the cuttings by the cooking liquor containing the said products and the delignification of the said cuttings.

40 Moreover, inside the grinding wheel, the chemical cooking liquor acts on the materials to be defibrated at the desired temperature and pressure in order to obtain an action on the ligneous incrustations of the said materials, with this important observation that the pressure and the temperature are not connected with each other, since the pressure is produced essentially by the centrifugal force and not by the temperature, as is generally the case when closed treatment chambers are used.

45 In order for the fibers not to be unduly shortened and to be expelled as soon as they have been reduced to a given length it is necessary to work with a relatively high concentration of fibers (concentration as weight of the fibers contained in the liquid phase) in the grinding zone in the vicinity of the grinding wheel, in order to facilitate the chemical and mechanical grinding action, and with a lower concentration in the extraction zone of the fibers in the vicinity of the screen. For example, there will be a concentration of 3 to 5% of fibers in the grinding zone and a concentration of 1 to 2% in the screening zone.

50 The invention will now be described in detail with reference to the accompanying drawings, of which

Fig. 1 represents a centrifugal defibrating apparatus according to the invention;

Fig. 2 represents diagrammatically the different cycles of the apparatus;

55 Figs. 3a and 3b represent in detail and in cross-section the centrifugal defibrator of Fig. 1.

Figs. 4 and 5 represent modifications of the defibrator and of the diluting means, the pre-impregnating means remaining those of Figs. 3a and 3b.

Referring to Fig. 1, 2 denotes an annular cylindrical grinding wheel clamped between two cheeks 3 and 4 of thick plate iron by bolts 7, the fixing being effected by wooden packing 5. A rotatable feed screw 33 which rotates inside a worm frame conveys the solid and liquid products and opens in the vicinity of the centre of the cheek 3 at a point where the pressure due to the centrifugal force is substantially zero. Inside the cylindrical space of the annular grinding wheel, vanes 9, which are carried by radial arms 10 and 10' and driven by a driving shaft 11 supported by bearings 12 and 13, can rotate. Belt pulleys 14 are mounted on the shaft 11. The belt 28 is driven by the motor 8.

Referring to Figs. 3a and 3b the shaft 11 for driving the vanes is a hollow shaft, the internal hollow part of which is separated into two parts 36 and 37 by a partition 38. The vanes 9 are flat and hollow blades which are parallel to the shaft 11 and occupy nearly the whole of the axial length of the grinding wheel. Each vane is carried, in relation to this shaft, by two radial arms 10 and 10', one of which, 10, which is fixed on the part 36 of the shaft 11, is also hollow and in communication with the inside part 36 of the shaft and the inside part of the vane which it carries.

The shaft 11 also carries a screening drum 42, the cylindrical surface of which passes in the vicinity of the internal longitudinal edges of the vanes 9. The part 37 of the shaft 11, which is situated inside the drum, is perforated with holes 15 and the internal longitudinal edge of the vanes is also perforated with holes 16 which have a tangential direction, i.e. through which the liquid issues in an orthoradial direction.

The operation of the defibrator is as follows:

The laminar cuttings are deaerated in an airtight chamber 47 and are then introduced into the centrifugal defibrator where they are ground in the grinding zone that is situated against the grinding wheel 2 where the fibers have a certain concentration. This concentration is reduced in the vicinity of the inlet into the screening drum 42 by the arrival of water through the hollow shaft 36, the hollow arms 10, the hollow vanes 9 and the holes 16. The discharge of the good fibers through the holes of the drum 42 is thus facilitated by the dilution which renders possible a separation of the fibers that facilitates their passage through the holes of the screening drum by preventing them from becoming stopped up. The discharge of the fibers is thus effected through the drum 42 and through the pipe 37, which is provided with a regulating valve 17 and a connection for a manometer 18. The fibers are thus led into a screen 19 (Fig. 2) which sorts the coarse pulp on one side and the fine pulp on the other side. The coarse pulp is recycled through the pipe 26 into the airtight chamber 47 and the fine pulp is sent through the pipe 27 into a conditioning or thickening filter 20 according to the process employed. The filter separates good thickened pulp which is available in the piping 21 from the clear water or from the cooking liquor to be recycled which is sent through the piping 22 into a tank 24. If chemical products are employed, the cooking liquor to be recycled is completed by an addition of concentrated cooking liquor which arrives through the piping 23 and it is sent back into the chamber 47 through the piping 25 and the valve 34.

In Fig. 4, the introducing screw is still denoted by 33, the grinding wheel is represented at 2, the lateral cheeks of the apparatus are represented at 3 and 4, the vanes are represented at 40 and their driving shaft is represented at 11. The vanes are secured to the shaft by arms 10 and 10'. The shaft 11, the arm 10 and the vanes 40 are hollow as in the case of Fig. 1. The grinding wheel does not occupy the whole of the axial length of the grinder and, in the extension of the latter, is situated a screening drum 48 which leads to an outlet piping 37.

The ends of the vanes which are close to the drum are perforated with tangential holes 41 and the supply of water, which takes place through these holes, enables the fibers to be diluted at the screening position.

In this modification, as the screen is further from the shaft of the centrifugal grinder than in the case of Fig. 3a, the internal reduction of pressure is greater and the laminar cuttings are better deaerated.

The modification shown in Fig. 5 is very much like the grinder shown in Fig. 3a. The only difference is that the screening drum 49 is stationary and that the shaft 44 is overhanging. The outlet piping 50 is stationary instead of being constituted by a hollow shaft.

It is pointed out that there may usefully be considered a selection of the fibers by displacement of the screening zone in the radial direction. It is consequently advisable for the screening drums 42, 48 and 49 to be fitted removably in the centrifugal grinders so as to be replaceable by other centrifugal screening drums with a different diameter and, if required, having perforations of different sizes.

Four examples of application of the process of the invention will now be given, the first relating to a mechanical grinding and the other three relating to grinding with chemical action. These examples apply especially to the grinding of hardwood for the manufacture of paper-making fibers.

Example 1

The grinding wheel has a grain that is similar to that of grinding wheels of grinders for mechanical paper stock.

Chips of poplar wood and water are introduced into the apparatus, with a speed of rotation of the vanes such that it creates a pressure of the order of 2 kgs. per sq. cm. to the manometer 18, the apparatus operating continuously.

The apparatus is provided with a drum 42 and a hollow shaft 37 comprising holes 43 and 15, having a diameter of 1.4 mm., which filters the discharge of the fibers in suspension in water.

The quantity of water and of cuttings is regulated so as to obtain a concentration of the fibers of the order of 4% against the grinding wheel and the rate of the water flowing from the holes 16 is regulated in order that this concentration should be reduced to 2% in front of the grating.

The magnitude of the rate of discharge and of the rate of recycling, on the one hand, and the supply of cuttings and of water, which is more or less hot, on the other, are regulated simultaneously for the purpose of maintaining, in the apparatus, a temperature of the order of 50 to 70° C.

Fibers of poplar are thus obtained which are perfectly utilisable in paper-making, particularly from the point of view of draining, breaking length and break and bleaching value.

Example 2

Cuttings of hardwood and a solution of NaOH are introduced into the airtight chamber in such proportions that the ratio of cooking liquor to wood is 4:1 and the ratio NaOH to wood is 10%. The stirrer 9-10-10' which drives the cuttings against the grinding wheel with a pressure that is developed by the centrifugal force, is rotated. The temperature rises progressively up to a temperature of between 50 and 100° C. at the same time as the centrifugal force creates the pressure in the grinding zone, this pressure favouring the penetration and the action of the delignifying liquid. This pressure may vary between 2 and 5 kgs. per sq. cm.

The yield of fibers is of the order of 80 to 90%.

The consumption of caustic soda is of the order of about 6% in relation to the weight of the fibers.

The cooking liquor is recycled continuously, and its concentration is readjusted as indicated in relation to Fig. 2.

Example 3

The solution of soda is replaced by an hydrotropic solution, for example an aqueous solution containing 33.3% of sodium xylenesulphonate.

The yield is of the order of 80 to 90%.

The hydrotropic solution is recycled continuously and its concentration is readjusted.

The lignin is precipitated from the solution when it has become saturated, and the hydrotropic solution is thus recovered.

Example 4

The solution is composed of neutral sodium sulphite and sodium carbonate in such quantities that the ratio Na₂SO₃/wood is 10% and the ratio Na₂CO₃/wood is 5%.

The yield is of the order of 80 to 90%.

The solution is recycled continuously and its concentration is readjusted.

The apparatus of the invention has been described in accordance with particular examples of embodiment. It is to be understood that modifications, which can easily be conceived by a person skilled in the art, are possible and are within the invention. It is particularly pointed out that the grinding wheel may have its axis vertical, that it could consist of removable elements that are liable to become worn out and have a suitable size of grain and are fixed on a stand, and that the filter may be placed in any position in the pressure zone. Finally, the delignifying action may be combined with a chemical bleaching action.

What I claim is:

1. Apparatus for defibrating wood chips to produce fibers suited for the production of paper, comprising a centrifugal defibrator, means for introducing into said defibrator a mixture of wood chips and a liquid medium while excluding simultaneous introduction of extraneous air, said centrifugal defibrator comprising a cylindrical chamber having abrasive particles secured to the internal cylindrical surface thereof, rotatable vanes for driving the wood chips and liquid medium outwardly against said abrasive particles, said vanes being hollow and formed with perforations, a screen constituted by a rotatable perforated drum secured to said vanes and positioned within said cylindrical chamber, means to move said vanes through a circular path adjacent the interior of said cylindrical chamber, means to remove liquid medium from said cylindrical chamber through said screen, means for supplying fresh liquid medium through said perforations of said hollow vanes to the immediate vicinity of said

screen whereby the fibers produced by the abrasive action of said abrasive particles upon said wood chips are diluted in the vicinity of said screen and those fibers which have been reduced to a given predetermined length will be selectively removed from said cylindrical chamber through said screen.

2. Apparatus as recited in claim 1 in which said perforated drum is stationary and located in extension of the axial length of the annular grinding wheel, leading to a peripheral stationary outlet piping.

3. Apparatus as recited in claim 1 in which said perforated drum is stationary and secured to one side of the grinding wheel, leading to a stationary outlet piping.

4. Apparatus for defibrating wood chips to produce

15 fibers suited for the production of paper, comprising an airtight chamber, means for introducing into said chamber a mixture of chips and a liquid medium without the simultaneous introduction of extraneous air, a centrifugal defibrator airtight, conveying means between said chamber and said centrifugal defibrator, said centrifugal defibrator comprising a cylindrical chamber having abrasive particles secured to the internal cylindrical surface thereof, vane means for driving the chips and liquid medium outwardly against said abrasive particles, said vanes being 20 hollow and formed with perforations, a screen constituted by a rotatable perforated drum secured to said vanes and positioned within said cylindrical chamber, means to move said vane means through a circular path adjacent the interior of said cylindrical chamber, means to remove 25 liquid medium from said cylindrical chamber through said screen, means for supplying fresh liquid medium through said perforations of said hollow vanes to the immediate vicinity of said screen whereby the fibers produced by the abrasive action of said abrasive particles upon said wood 30 chips are diluted in the vicinity of said screen and those fibers which have been reduced to a given predetermined length will be selectively removed from said cylindrical chamber through said screen.
